H. Aiken

Shaving Leather.

Patented June 12, 1835.

Herrick, Then of Middlesex Co. Massachusetts
Sellers Patent

Whereas referred to in the sellers Patent and machinery part of
the same containing a description in the words of the said Herrick
Aiken himself of his improvement over machine for
splitting and planing leather called "Aiken's machine for split-
ting, planing or sharpening leather."

Be it known that I, Herrick Aiken of Dracut, County of
Middlesex, State of Massachusetts have made an improvement
in the useful art, being a machine for splitting and planing or
leather called "Aiken's machine for splitting or planing or sharp-
ening leather, which is described as follows: The machine con-
sists of the following principle parts. The frame, the knife,
the spring seat the working regulator, the regulating screw,
and the screw for confining the blade. The frame is made of
cast iron consisting of two pillars, or ends, connected by a cross piece
the ends to be about 8 inches long, and the cross piece about 10
inches. There is a projection on each end, containing two pins
for letting into a bench, for confining it to its place when in
use. Also on the opposite side are two other projections, having
grooves in them for receiving the ends of the knife. One groove
is made semicircular, and the other is made square, with a follower
to bear against the end of the knife. The last described projec-
tion containing a screw to project against the follower to confine
the knife. The knife is a straight blade with the ends be-
velled, and is confined in the grooves in the frame by the means
of the screw before mentioned. The spring seat is placed in the
frame before the blade for passing the leather against the regulat-
tor. The seat is supported by a spiral spring in each pillar.
The working regulator is made lined hollow semi circular
pended on a leg in base supported in the frame by spiral spring.
It is moved up and down by two regulating screws, one on either

end of each pillar, which operation thins the leather, these are steps on the regulator to keep it to its place. Operation. The leather to be split is skived, being cut to its proper length and width and the regulator adjusted to the thickness required in leather partly, and which opens a space to admit the leather. It is then turned back upon the leather, and the leather drawn through by hand and thus reduced to its required thickness. This regulator also measures the thickness of bedding the ends of the strips. The invention here claimed and desired to be secured by letters patent consists in the arrangement and adaptation of the several parts of the machine so as to produce the one before described, but I particularly claim the method of confining the knife, and the construction of the Regulator.
